No. 617,339.

Patented Jan. 10, 1899.

A. T. JOHNSON.

SASH HOLDER.

(Application filed Jan. 20, 1898.)

(No Model.)

UNITED STATES PATENT OFFICE.

ARTHUR T. JOHNSON, OF TRAVERSE CITY, MICHIGAN.

SASH-HOLDER.

SPECIFICATION forming part of Letters Patent No. 617,339, dated January 10, 1899.

Application filed January 20, 1898. Serial No. 667,224. (No model.)

To all whom it may concern:

Be it known that I, ARTHUR T. JOHNSON, residing at Traverse City, in the county of Grand Traverse and State of Michigan, have 5 invented a new and useful Sash Holder, of which the following is a specification.

My invention relates to that class of devices known as "sash-holders," and has for its object to furnish a simple, cheap, durable, and 10 effective sash-holder which by simple movements may be adjusted to lock the sash against upward movement or against downward movement or against either upward or downward movement or to permit the sash to be 15 moved freely either up or down.

With this object in view my invention consists in a sash-holder comprising a dog or locking-lever with a circular opening through it near its rear end and stop-pins projecting 20 from its face, an eccentric adapted to be placed in said opening pivoted to the window-sash by a screw and having an operating-handle, and a spring secured to the sash adapted to rest on the outer surface of the dog and be 25 engaged with either of the stop-pins, as may be desired.

In order to enable others skilled in the art to which my invention most nearly appertains to make and use the same, I will now proceed 30 to describe its construction and operation, having reference to the accompanying drawings, forming part of this specification, in which—

Figure 1 is a perspective view illustrating my invention in practical operation upon a 35 window-sash. Fig. 2 is a view in side elevation of my invention detached from the sash, the edge of the window-frame being indicated by a line and the lock adjusted to prevent 40 downward movement of the sash. Fig. 3 is a similar view with the parts adjusted to prevent raising of the sash. Fig. 4 is a similar view with the parts adjusted to lock the sash against either up or down movement. Fig. 5 45 is a detail perspective view of the eccentric detached.

Like letters of reference indicate the same parts wherever they occur throughout the drawings.

Referring to the drawings by letters, A indicates the window-frame, and B the sash.

C indicates a dog or locking-lever which is adapted to be pivoted to the sash in position to bring the end face in contact with the frame. This end face for the greater portion 55 of its length is straight, as at D, and each end is curved, as at E and F. Projecting from its face are three stop-pins G, H, and I. A spring K is secured to the sash by a screw L and rests upon the outer face of the locking-lever C. 60 The locking-lever is pivoted upon a block M, which in turn is pivoted to the sash by means of a screw N, passing through a bore O, eccentrically located in the block, whereby the block becomes an eccentric, a handle P being provided on one edge thereof, which serves the 65 double purpose of manipulating the block on its pivot and assisting in holding the locking-lever C in position on the sash.

The construction of my improved sash-holder will be readily understood from the foregoing description and its operation may be described as follows: When the spring K is adjusted to bear under the stop-pin H, as shown in Fig. 4, the locking-lever will be retained in a horizontal position, and while in this position when the handle P of the eccentric block M is turned to its upward position, which will bring a greater diameter of the eccentric block between its attaching-screw 75 and the face of the frame, a flat central portion D of the locking-lever will be brought into forcible contact with the frame A and will securely lock the sash against movement either up or down. Without changing the 80 adjustment of the spring K the handle P of the eccentric block may be turned down, which will bring the shorter diameter of the eccentric block in the direction of the face and withdraw the end of the locking-lever from contact with the frame, leaving the sash free to be moved either upward or downward. When, however, the spring K is adjusted to bear under the lower stop-pin I, as shown in 85 Figs. 1 and 2, and the handle P turned to bring the lesser diameter of the eccentric block in the direction of the frame, the contact of the locking-lever will be elevated and the lower curved portion F brought into contact with the frame. In this position the sash 90 will be free to be moved upward or locked against moving downward. When, however, 95

the spring K is adjusted to bear upon the top of the stop-pin G, as shown in Fig. 3, and the handle P of the eccentric block moved downward to withdraw the central flat portion of the contact end of the locking-lever from the frame, the upper curved portion E of the contact-face will bear against the frame and lock the sash against upward movement, while leaving it free to be moved downward. When the locking-lever is in either of the positions shown in Figs. 1, 2, or 3, the sash may be locked against movement in either direction by simply turning up the handle of the eccentric block, which movement, as before explained, will turn the greater diameter of the eccentric block toward the frame and firmly lock the flat surface D of the contact end of the locking-lever against the frame.

From the foregoing description of the construction and operation of my invention it will be obvious that I have produced a simple, cheap, strong, durable, and effective sash-holder which will fulfil all the objects of my invention, and while I have described what I consider to be the best means for carrying out my invention I do not wish to be understood as restricting myself to the exact forms and arrangements shown, but hold that any slight changes or variations, such as might suggest themselves to the ordinary mechanic,

would properly fall within the limit and scope of my invention.

It will of course be understood that my invention may be applied by pivoting the locking-lever and eccentric block to the frame, so as to bring the contact end of the locking-lever against the sash, the construction and arrangement of all the various parts being identically the same as hereinbefore described.

Having thus described my invention, what I claim as new, and desire to secure by Letters Patent, is—

The combination with the sash, of the locking-lever having its contact end formed with a flat surface and curved upper and lower surfaces, stop-pins arranged in a vertical line on the face of the locking-lever, a spring secured to the sash and bearing upon the face of the locking-lever in position to engage either of the stop-pins, a cylindrical block upon which the locking-lever is pivoted having an eccentric bore, a screw passing through the eccentric bore of the cylindrical block and projecting over the face of the locking-lever, substantially as described.

ARTHUR T. JOHNSON.
